[57] CLAIM

The ornamental design for an athletic shoe sole, as shown.

DESCRIPTION

FIG. 1 is a top plan view of an athletic shoe sole showing my new design;

FIG. 2 is a left side elevational view thereof;

FIG. 3 is a bottom plan view thereof;

FIG. 4 is a rear elevational view thereof;

FIG. 5 is a front elevational view thereof;

FIG. 6 is a right side elevational view thereof;

FIG. 7 is a cross-sectional view as taken from line 7—7 of FIG. 3.
